UNITED STATES PATENT OFFICE.

MOÏS H. AVRAM, OF NEW YORK, N. Y., ASSIGNOR TO STANDARD SILICA BRICK MACHINERY COMPANY, OF WILMINGTON, DELAWARE.

APPARATUS FOR HYDRATING LIME.

1,157,284.

Specification of Letters Patent.

Patented Oct. 19, 1915.

Application filed September 16, 1913. Serial No. 790,011.

To all whom it may concern:

Be it known that I, Moïs H. Avram, a citizen of the United States, and a resident of New York city, Manhattan, county of New York, and State of New York, have invented a new and useful Apparatus for Hydrating Lime, of which the following is a specification.

This invention relates to a novel apparatus for hydrating lime, in a quick, reliable and economic manner, the apparatus comprising essentially a barrel or drum which is so constructed that it may be readily charged with unslaked lime, and that the hydrated lime may be quickly discharged from the drum while the latter is in rotation. In this way any undue delay is avoided, while at the same time power is economized, as for starting the comparatively heavy filled drum, a motive power is required which is far in excess of that necessary during the normal operation of the apparatus. The introduction of the lime into a rotating drum has the advantage that the charge is automatically and evenly distributed within the interior of the drum, thereby insuring uniform hydration. Furthermore, the discharge of the hydrated lime is accelerated, if the drum continues in its rotation particularly as effective means are provided that cause said lime to slide toward the exit opening. The quick removal of the lime from the drum has another advantage in that the lime has no time to cool before or while being discharged but is delivered at a high temperature, so that any condensation of moisture upon said lime is prevented, and a perfectly dry product is obtained.

In order to maintain a high temperature within the drum during hydration, said drum is jacketed, it being provided with double walls between which an air space is formed, that serves as an insulator against the radiation of heat, so that the superheated steam introduced into or generated within the drum retains its state and does not become condensed. Before opening the barrel for emptying the same, this superheated steam, however, is admitted into the jacket so as to exteriorly heat the drum during the discharge of the hydrated lime.

Additional novel features of my improved apparatus are brought out in the annexed

specification and claims, reference being had to the accompanying drawings in which— 55

Figure 1 is a side view of my improved hydrating apparatus, Fig. 2 an enlarged longitudinal section thereof, and Fig. 3 an enlarged cross section on line 3—3, Fig. 1.

My improved hydrator comprises essentially a double-walled or jacketed drum A, the inner wall 10 and outer wall 11 of which taper toward the ends of said drum as illustrated in Figs. 1 and 2. Between walls 10 and 11, a heating chamber 12 is formed that communicates with the chambers 13 formed between the inner and outer end walls 14, 15, respectively, of the drum. To walls 14, 15 are secured a pair of trunnions 16, 17 rotatably mounted in bearings 18, 19. Drum A is provided with suitable means for rotating the same such as a gear wheel A¹ which receives motion in any suitable manner.

Although the openings for introducing 75 the unslaked lime and for discharging the hydrated lime may be located at any convenient point of the drum, I prefer to feed the raw lime through one of the trunnions, while the discharge of the hydrated lime is 80 effected through an opening formed in the side walls of the drum and arranged at or near the center thereof.

As it is of the greatest importance for a 85 thorough and uniform hydration of lime that a predetermined charge of unslaked lime and a likewise predetermined quantity of moisture be admitted into the hydrator, an automatic weighing or measuring device B is provided. The latter separates from 90 the bulk of the lime, which is conveyed to device B through a suitable chute 20, such a quantity as constitutes a single charge of the hydrator. From the weighing device B, the lime is delivered into a grinding mill or 95 crusher C in which it is reduced to particles of small grain, say of $\frac{1}{8}$ to $\frac{1}{2}$ of an inch diameter. As the weighing device and the crusher do not form part of the present invention, they are only diagrammatically 100 shown in Fig. 1. The reduced lime is discharged from crusher C into a feed hopper 21, the lower end of which opens into a tapering central opening 22 of trunnion 16. Opening 22 is adapted to be closed by a 105 conical valve 23 which is secured to a rota-

table and reciprocable, hollow spindle 24. The latter, passing through a corresponding aperture of hopper 21, is journaled in a stationary bearing 25 forming part of the 5 machine frame. The outer end of spindle 24 passes through a stuffing box 26 and is received within a corresponding bore 27 of a stationary cylinder 28. The latter communicates through a pipe 29 controlled by 10 cock 30 with suitable steam or water supplying means 31. These means may be of any suitable construction which permits a regulable quantity of moisture to be introduced into drum A through pipe 29, cylinder 28 15 and hollow spindle 24.

For opening and closing valve 23, spindle 24 is provided with a relatively fixed collar 32, a circumferential groove 33 of which is engaged by the pin 34 of a shipping lever 20 35. The latter is fulcrumed at 36 to a bracket 37 that also serves to support cylinder 28. To the free end of lever 35 is pivoted a shipping rod 38 which may be intermittently reciprocated in any suitable manner. 25

It will be readily understood that upon the opening of valve 23 the reduced lime discharged from crusher C will be fed into drum A. After the same has thus been 30 charged with the desired quantity of lime, valve 23 is closed. The moisture necessary for hydrating the lime may be admitted into the drum during or subsequent to the introduction of the lime by properly manipulating cock 30.

The trunnion 17 of the hydrating drum is provided with three longitudinal bores 39, 40 and 41 of which bore 39 communicates with the interior of drum A, while bores 40, 40 41 open into one of the end jackets or chambers 13. The outer end of bore 39 opens into a circumferential groove 42 of the outer reduced section 43 of trunnion 17, said section being received within the corresponding bore 45 of a stationary block 44. Groove 42 communicates with one leg of an inverted U-shaped duct 45 formed in block 44 and controlled by a cock 46. The other leg of duct 45 communicates with a circumferential 50 groove 47 formed in trunnion-section 43 and communicating with bore 40. A pipe 48 controlled by a cock 49 opens into duct 45 and serves for admitting live steam into said duct. Bore 41 opens into an annular groove 55 50 of section 43 which in turn communicates with a discharge pipe 51 controlled by a cock 52.

After the lime has been completely hydrated, during which process the pressure 60 within the hydrating chamber 53 may be observed by a gage 54 connected to duct 45, cock 46 is opened to admit the superheated steam formed during the hydrating process within chamber 53 into jacket 12, 13, the air 65 previously contained in said jacket being

discharged through duct 41, groove 50, pipe 51 and open cock 52. In order to cause the steam to completely fill the jacket before being discharged, staggering longitudinal partitions 55 may be provided in said jacket. 70

After the heat generated during the hydration of the lime has thus been advantageously employed for exteriorly heating the hydrating chamber 53, the hydrated lime is discharged by the following means: Drum 75 A is provided with a peripheral discharge opening A² controlled by a conical valve or gate 56. The latter is securely attached to the inner end of a screw stem 57 loosely passing through a bearing 58. The latter 80 forms part of a U-shaped frame which is secured to drum A by screws 59. Stem 57 is adapted to freely reciprocate within bearing 58 while its rotation therein is prevented by a groove and feather connection 60. 85 Screw stem 57 is engaged by an internally threaded pinion 61 which is held against axial displacement by a pair of relatively fixed keepers 62 engaging a corresponding groove of pinion 61. The latter is adapted 90 to be engaged by either one of a pair of curved racks 63, 64, depending from a slide 65 which is reciprocally mounted in a fixed guide 66. To slide 65, there is pivoted at 67 a shipping rod 68 which may be manipulated 95 in any suitable manner. For discharging the hydrated lime, rod 68 is shifted toward the left (Fig. 2) so as to bring rack 64 into the path of pinion 61. The latter, while revolving with drum A, will thus engage rack 100 64 to be rotated. The diameter of pinion 61 and the length of rack 64 is such, that during a single engagement of the pinion with the rack, gate 56 is fully opened. After the pinion has cleared the rack, slide 65 is 105 returned into its normal central position by correspondingly operating shipping rod 68, to permit a subsequent unimpeded passage of pinion 61 between racks 63, 64. During 110 the rotation of drum A, the hydrated lime is discharged through opening A² into a suitable hopper 69 which conveys the product to the place desired. While thus discharging the lime, the drum is heated by the superheated steam admitted into jacket 12, 13 from the hydrating chamber, so that the lime retains its high temperature and any condensation of moisture upon the same is effectively prevented. Should the steam admitted from the hydrating chamber into the 115 jacket be insufficient for heating said chamber during the discharge of the lime, live steam may be introduced into said jacket by opening cock 49, cock 46 having been previously closed. After all lime has been 120 discharged from drum A, rod 68 is shifted toward the right so as to bring rack 63 into the path of pinion 61 whereby gate 56 is returned into its original position to close 125 opening A², as will be readily understood. 130

Cocks 49, 52 are now closed and valve 23 is opened to admit a fresh charge of unslaked lime into the hydrating chamber, whereupon the operation described is repeated.

I claim:

1. Apparatus for hydrating lime comprising a rotary drum, a surrounding jacket, means for introducing predetermined quantities of unslaked lime and moisture into said drum, and means for conducting the steam generated during hydration from the drum into the jacket.

2. Apparatus for hydrating lime comprising a rotary drum, a surrounding jacket, means for introducing predetermined quantities of unslaked lime and moisture into said drum, means for conducting the steam generated during hydration from the drum into the jacket, and means for subsequently discharging the hydrated lime from the drum.

3. Apparatus for hydrating lime comprising a rotary drum, a surrounding jacket, a valve-controlled duct connecting the interior of the drum with the jacket, and a valve-controlled duct connecting said jacket with the atmosphere.

4. Apparatus for hydrating lime comprising a rotary drum, a surrounding jacket, a pair of trunnions at the ends of the drum, means for introducing unslaked lime and moisture through one of said trunnions, and means in the other trunnion for connecting the jacket with the interior of the drum and with the atmosphere.

5. Apparatus for hydrating lime comprising a rotary drum, a surrounding jacket,

means for introducing unslaked lime and moisture into the drum, means for connecting the jacket with the interior of the drum and with the atmosphere and a steam supply pipe adapted to be connected with the jacket.

6. Apparatus for hydrating lime comprising a rotary jacketed drum, a trunnion at one end thereof and having a coniform opening, a rotatable and axially movable hollow spindle, a conical valve carried thereby and adapted to close the opening, and a moisture supply pipe adapted to communicate with the interior of the spindle.

7. Apparatus for hydrating lime comprising a rotary drum, a trunnion at one end thereof and having a coniform opening, a rotatable hollow spindle centered within said opening, a valve carried by the spindle and adapted to close the opening, a cylinder embracing the outer end of the spindle to communicate with the cylinder, and means for reciprocating the spindle.

8. Apparatus for hydrating lime comprising a rotary drum, a trunnion at one end thereof and having a coniform opening, a feed hopper entering said opening, a hollow spindle centered within the opening, means for rotatably supporting the spindle, a valve carried by the spindle and adapted to close said opening, a cylinder embracing the outer end of the spindle, a moisture supply pipe adapted to communicate with the cylinder, and means for reciprocating the spindle.
